COASTER WAGON

Oscar Christian Albrecht, Hustisford, Wis.

Application December 19, 1934, Serial No. 758,299

2 Claims. (Cl. 280—124)

This invention relates to the broad classification embodying play things in general and has more specific reference to so-called coaster wagons and similar toy vehicles and conveyances of 5 the type generally employed by children.

The principal novelty is exemplified in the novel wheel ensemble and unique mounting means therefor. More specifically stated, however, I have evolved and produced a simple and 10 economical wheel arrangement embodying a "knee-action" principle, whereby to provide a coaster wagon having yieldable smooth riding properties similar to those found in present day automobiles equipped with so-called knee action 15 wheels.

In keeping with the inventive conception, I have developed a special light weight, yet durable selection and coordination of features wherein in each wheel is individually and swingably mounted in such a manner as to compensate for irregularities in the surface traversed so as to provide a high speed, easy riding coaster wagon possessed of greater traction and relieving the 20 rider of needless shock and jar.

25 The preferred embodiment of the invention is pictorially illustrated in the accompanying drawings in which:

Figure 1 is a bottom plan view of a toy coaster wagon or equivalent vehicle equipped with my 30 invention.

Figure 2 is a longitudinal sectional view showing in detailed elevation the individual spring adaptation and wheel mounting means.

Figure 3 is a rear end elevation of the wagon.

Figure 4 is a detail perspective view of one of the arched attaching frames.

Referring now to the drawings by distinguishing reference numerals it will be observed that the body of the coaster wagon, which is conventional, is denoted by the numeral 5. The front wheels are indicated at 6 and the rear wheels at 7. It is to be observed however, that the wheel assemblies at the front and rear are virtually the same except that the front structure is 40 swivelly mounted for steering purposes. Or as stated otherwise, each wheel assemblage comprises a substantially U-shaped arch or frame 8 of the type illustrated in Figure 4. The depending end portions 9 may be described as arms 45 and the lower end portions thereof are of forked construction. This is accomplished by simply attaching outside clips or cleats 10 to the lower end portion through the instrumentality of bolts 50 and the spacing members 11. This arrangement 55 serves to accommodate the fulcrum bolt 12 which

bolt may also be utilized to hold in place the down-turned ends of the horizontal cross-brace 13. As before pointed out, each wheel is individually mounted and the means for accomplishing this is the same in each instance and a description of one arrangement will suffice for all. To begin with, I call attention to the rocker arm 14 which is slightly bowed in a longitudinal direction. The outer end portion 15 carries an axle 16 to accommodate the adjacent wheel. At this end there is 10 an equalizing light weight coiled spring 17. This spring is anchored at its lower end on the outward extension 15 at a point adjacent the axle. The upper end of the spring is attached to an anchoring bar 18 rigidly fastened to the adjacent 15 arm of the arch just below the bottom of the body of the wagon. The main resisting or knee action spring is indicated at 19 and this is quite heavy in comparison to the spring 17. One end, that is the lower end, is attached to the inner 20 extension 20 of the rocker arm and the upper end is attached to the aforementioned hanger or anchoring bar 18. Obviously, the rocker arm, as a unit, is fulcrumed or pivoted intermediate its ends on the bolt 12. Both of the springs are of the 25 coiled contraction type and cooperate in companionate relationship, the spring 19 allowing the wheel to fly bodily up toward the body of the wagon when obstruction is encountered and the spring 17 being more in the nature of a flat take- 30 up spring to prevent the outer end extension 15 from dropping down too far when the wagon is bodily lifted or carried about from place to place. It is evident however, that this double acting arrangement is such that the springs provide their 35 requisite or proportionate share to operate efficiently in conjunction with the rocker arm and other features to allow the elastic compensating knee action of the wheel. It is evident, therefore, that these parts have been carefully selected and 40 properly matched and coordinated to provide the desired continuity and completeness of action. The result is that all of the wheels on the wagon have individual compensating or accommodating facilities making it possible to provide the de- 45 sired simple, economical knee action principle for coaster wagons and analogous toys such as "scooters", tricycles or even a baby carriage. It would seem therefore, that an invention of this type as applied to play things is a revelation, if 50 not an innovation and that it is something which is practical and susceptible of unqualified endorsement by the trade. I shall not, however, delve into other commercial phases of the invention since, after all, it is the particular arched 55

frame construction and double acting spring and rocker arm means that constitute the specific invention here offered as an appreciable contribution to the art.

5 It might be mentioned that the rear frame is rigidly bolted or attached to the corresponding end portion of the body while the central portion of the front frame is pivotally attached as at 22 and the arrangement includes a wear disk 10 or plate 23. This provides the desired steerable mounting for the front frame. This is of no consequence in so far as it relates to the novelty of the claims.

15 It is thought that persons skilled in the art to which the invention relates will be able to obtain a clear understanding of the invention after considering the description in connection with the drawings. Therefore, a more lengthy description is regarded as unnecessary.

20 Minor changes in shape, size and rearrangement of details coming within the field of invention claimed may be resorted to in actual practice, if desired.

What I claim as new is:

25 1. A vehicle of the class described comprising a body, inverted yokes depending from the body each providing a pair of spaced depending limbs, the lower ends of which are forked, an arcuate shaped rocker arm passing through each fork the

concave edge uppermost, a brace bar extending between the lower ends of each pair of limbs, a bolt passing through ends of the brace bar, through the prongs of the fork to an intermediate part of the rocker arm pivoting the arm in 5 the fork, a horizontal arm connected to the upper portion of each limb, a wheel carrying spindle at one end of each rocker arm, a heavy spring at one end connected with the other end of the rocker arm and its other end connected 10 to the adjacent end of the horizontal arm and a light spring connecting the other end of each rocker arm with the other end of the horizontal arm.

2. In a vehicle a depending part, an arcuate 15 shaped rocker arm pivoted intermediate its ends to the lower end of said depending part, the concave edge of the arm uppermost, a cross piece connected to the upper part of the depending portion, a wheel carrying spindle at one end of 20 the rocker arm, a heavy spring having one end connected with the opposite end of the rocker arm and its other end connected to the adjacent end of the cross piece and a light spring connecting the opposite end of the cross piece to the 25 other end or spindle carrying end of the rocker arm.

OSCAR CHRISTIAN ALBRECHT.
